[57] **CLAIM**

The ornamental design for a combined dispensing bin and support assembly, as shown and described.

DESCRIPTION

FIG. 1 is a top, front, left side perspective view of a combined dispensing bin and support assembly showing my new design;

FIG. 2 is a left side elevation thereof, the opposite side being a mirror image;

FIG. 3 is a front elevation thereof;

FIG. 4 is a top plan view thereof;

FIG. 5 is a rear elevation thereof;

The undisclosed bottom view is plain and unornamented.

FIG. 3**FIG. 2****FIG. 4****FIG. 1****FIG. 5**
